UNITED STATES PATENT OFFICE.

WALTER P. MURPHY, OF CHICAGO, ILLINOIS.

RUNNING-BOARD SADDLE.

1,011,233.

Specification of Letters Patent. Patented Dec. 12, 1911.

Application filed October 7, 1910. Serial No. 585,751.

To all whom it may concern:

Be it known that I, WALTER P. MURPHY, a citizen of the United States, and a resident of the city of Chicago, in the county of Cook and State of Illinois, have invented a new and useful Improvement in Running-Board Saddles, of which the following is a specification.

This invention relates to freight cars, and more particularly to the means for supporting and securing the running-boards on the roof of the car.

Running-boards are usually secured longitudinally of the car roof at the ridge or middle thereof to wooden saddles which are shaped on their lower sides to fit the sloping sides of the roof and having flat upper faces. The boards being secured by nails frequently become loose at their ends so that the same spring or warp above the surface of the adjacent running-board, and cause the brakeman or trainman to trip in running over the cars. It is desirable to make the running-boards of long planks extending in one piece the full length of the car, but because of the length of certain cars this is more or less impracticable and the running-boards are commonly made of shorter planks requiring two or more to extend the length of the car. This necessitates the securing of the abutting ends of the alined planks to the saddle.

The principal object of my invention is to provide a simple and inexpensive device suitable for securing the running-boards to the saddles and to prevent the nails from working out, and to attain certain advantages hereinafter more fully appearing.

The invention consists in the parts and in the arrangements and combinations of parts hereinafter described and claimed.

In the accompanying drawings which form part of this specification and wherein like symbols refer to like parts wherever they occur, Figure 1 is a fragmentary transverse section through a car roof adjacent to a running-board saddle, illustrating an adaption of my invention; Fig. 2 is a fragmentary top plan view partly in section; Fig. 3 is a plan view of the retaining strap detached; Fig. 4 is a view showing a modification of my invention; Fig. 5 is a perspective view of a filler block used in connection with the construction shown in Fig. 4; Fig. 6 is a top plan view of the construction shown in Fig. 4; Fig. 7 is a view partly

in elevation showing a further modification of my invention; Fig. 8 is a top plan view of the construction shown in Fig. 7; and Fig. 9 is an end view of the latter construction.

Referring now more particularly to Figs. 1 to 3, inclusive, an ordinary wooden running-board saddle 1 is illustrated as mounted on the car roof 2. The running-boards 3 are secured to the saddles 1 by nails 4 or, obviously, the same may be secured by screws. A metal strap 5 is secured over the running-boards 3 and the same is offset and depressed as at 6 between the running-boards; and said offset portions are secured preferably by screws 7 to the saddle 1. In order to adapt the strap to receive the screws in the narrow space between the running boards, the bottom of the depression is made straight, in order to rest flatwise against the saddle, and as long as the space will admit; that is to say, the offset is substantially rectangular. The opposite ends of the strap 5 are bent down as at 8 against the ends of the saddle, and secured thereto. Preferably the end portions of the strap are slotted longitudinally and said slotted or bifurcated end portions 9 are folded over diagonally against the strap so that they project in opposite directions therefrom, as shown more clearly to the right of Fig. 3. These end portions 9 are then turned inwardly against the opposite side faces of the saddle and nailed or bolted thereto as at 10. It is preferable to use the through bolts as shown. So, too, instead of using the screws 7 to secure the depressed portions of the strap between the running-boards, obviously, bolts may be substituted therefor.

As shown in Figs. 4 to 6, inclusive, filler blocks or castings 11 are secured on the saddle between the running-boards. These filler blocks are preferably secured by bolts 12 and their upper faces lie flush with the top faces of the running-boards. The filler blocks are provided at their opposite ends with inwardly overhanging shoulders or undercut lugs 13; and instead of offsetting and depressing the strap 5^a, the same is slipped under the inwardly overhanging shoulders 13 on the filler blocks 11 which thereby retain said strap against the top faces of the running-boards. The end construction of the strap 5^a is identical with the strap 5 above described.

In Figs. 7 to 9, inclusive, the strap 5^b is

similar to the strap 5 except that the opposite marginal portions 14 are extended beyond the opposite side faces of the saddle 1. In this construction, bolts 15 are inserted 5 through perforations in said marginal portions 14 and vertically alining holes in the running-boards, and said bolts 15 are secured by nuts 16 on their lower ends. By this arrangement the strap is more securely 10 held against buckling. The end portions of the strap 5^b are arranged similarly to those of the strap 5.

By the foregoing constructions, running-boards may be securely held on the ordinary 15 wooden saddles as the securing nails are prevented from working out. The retaining straps may also, obviously, be applied on a metal saddle without departing from my invention; and, obviously, the device admits 20 of considerable modification without departing from my invention. Therefore, I do not wish to be limited to the specific constructions and arrangements shown.

What I claim is:

- 25 1. In a freight car, the combination with a running-board saddle, of running-boards nailed thereon, and a metal strap laid transversely over said running-boards and the securing nails therefor, the ends of said 30 strap being slit lengthwise and turned down over the ends of the saddle and the slit portions being folded diagonally and bent around against the sides of said saddle, and horizontal bolts extending through said 35 saddle and the slit end portions of said strap and secured to said saddle.
2. In a freight car, the combination with a running-board saddle, of running-boards, devices for securing said boards to said 40 saddles, and a metal strap laid transversely

over said running-boards and the securing devices, the opposite end portions of said strap being bent down against the ends of said saddle and having extensions bent inwardly and secured to the opposite side faces of said saddle.

3. The combination with a running-board saddle, of running-boards secured thereon, and a metal strap laid transversely over said running-boards and having its opposite ends 50 turned down and secured to said saddle, the side marginal portions of said strap being extended laterally on the sides of the saddle and secured to the running-boards.

4. The combination with a running-board saddle, of running-boards secured thereon, a strap laid transversely over said running-boards and secured at its opposite ends to said saddle, and filler blocks secured on said saddle between said running-boards, said 60 filler blocks having retaining devices arranged and adapted to engage the marginal portions of said strap and hold the latter in place.

5. The combination with a running-board saddle, of running-boards secured thereon, and a metal strap laid transversely over said running-boards, the opposite end portions of said strap being turned down against the ends of said saddle, and said opposite end 70 portions of the strap being slitted longitudinally and bent inwardly against the opposite side faces of said saddle and secured thereto.

Signed at St. Louis, Mo., this 29th day 75 of September, 1910.

WALTER P. MURPHY.
